UNITED STATES PATENT OFFICE.

EDWARD E. GOLD, OF NEW YORK, N. Y., AND WILLIAM H. IVERS, OF ST. LOUIS, MISSOURI, ASSIGNEES TO GOLD CAR HEATING & LIGHTING COMPANY, OF NEW YORK, N. Y., A CORPORATION OF NEW YORK.

HEATING SYSTEM FOR RAILWAY CARS.

1,402,063.

Specification of Letters Patent. Patented Jan. 3, 1922.

Application filed July 1, 1919. Serial No. 307,962.

To all whom it may concern:

Be it known that we, EDWARD E. GOLD and WILLIAM H. IVERS, both citizens of the United States of America, the former residing in the borough of Manhattan, city, county, and State of New York, and the latter residing in St. Louis, in the county of St. Louis and State of Missouri, have invented certain new and useful Improvements in Heating Systems for Railway Cars, of which the following is a specification:

This invention relates to means for heating railway cars, being especially adapted for the heating of freight cars, such, for example, as those of the refrigerator type used for the transportation of perishable fruits, vegetables and other produce. To prevent the freezing of such produce during winter transportation, it is desirable to heat the interior of the car by the application of mild heat just sufficient to avoid the possibility of freezing. For this purpose it is desirable to utilize steam taken from the locomotive boiler, as in the heating of passenger cars. It is also desirable to provide for a certain storage of heat in order to bridge over intervals when the car or train is detached from the locomotive. For this purpose heat storage radiators are preferably used, in which the water of condensation is accumulated and serves as the heat storage medium. In the use of such radiators it becomes necessary to provide means for avoiding the freezing of the condensation water.

The present invention is designed to accomplish these ends in a manner affording practical means for application to freight cars of the existing refrigerator car type. The construction and novel features will be developed as the description proceeds.

Referring to the accompanying drawings,—

Figure 1 is a fragmentary transverse section of the lower portion of a refrigerator car, showing the preferred application of the invention thereto;

Fig. 2 is a fragmentary longitudinal section mainly in the plane of the line 2—2 in Fig. 1;

Fig. 3 is a vertical mid-section of a drainage trap.

Referring to the drawings, A designates the floor, and B the side walls of the freight

car. Beneath the floor is a radiator chamber C. Within the floor structure are provided flues D D for circulating hot air from the chamber C to the remote portions of the car, and any suitable number of return flues E E. The drawings make no attempt to illustrate these flues in detail, nor the course of the outflowing heated air or returning cooler air, since such flue constructions are well understood. The longitudinal return flues E communicate with a transverse return flue E' which in turn discharges into a drop flue F leading to the bottom of the chamber C.

Within the chamber C is a heat storage radiator G. There may be any suitable number of these, two such radiators being shown. These radiators are tanks or reservoirs of any suitable construction, adapted to receive steam and condensation water. They are spaced suitably apart and sufficiently separated from the walls of the chamber C to permit the free upward circulation of air between and around them. Thus, whether the radiators G contain steam or hot condensation water, they serve as means for heating the air in the chamber C, so that this air may circulate throughout the flues in the car floor and thereby impart a mild heat to the car to protect its contents from freezing; the hot air as partially cooled returns through the flues E E' and F to the bottom of chamber C to be again heated and re-circulated.

Steam from the locomotive is supplied by means of a longitudinal train pipe H, as in any system for heating passenger cars. From this pipe is led a branch pipe I, preferably near the middle of the car, and in this branch pipe is introduced preferably a pressure reducing valve J of any suitable construction, whereby to diminish the pressure from the varying pressure in the train pipe to a uniform pressure, say for example, of 20 pounds (more or less). This steam-admission pipe I leads to an inlet valve K which controls the admission of steam to the radiators. With two radiators, as shown, the pipe I' leading from the valve K has two branches I² entering the radiators at one end and passing interiorly of them, preferably through to the opposite end, then up toward the top and back toward the entering end, as clearly shown in Fig. 2, and termi-

nating in an upturned portion opening near the top of the radiator shell. Thus the steam is admitted to both radiators. The several pipes I^2 , I' , I , drain to a low point L , where 5 is provided a gravity drainage trap M of the ordinary well-known construction, whereby when the steam is shut off and the pressure falls, this trap may open and drain off any water from these pipes, so as to prevent 10 freezing.

A pipe N communicates with the interiors of the two radiators at their tops, and extends down to a point suitably beneath the radiators, terminating in a thermostatic 15 drainage trap P of any ordinary or known construction. This trap is preferably of the kind which can be set to either function normally as a thermostatic trap, or to blow off steam. The construction shown in U. S. 20 Patent No. 1,050,210, dated January 14, 1918, is a suitable construction for this purpose. The trap discharges downwardly through a drip pipe or horn P' , which is preferably provided with a subdividing partition Q to provide ventilation, as set forth 25 in said patent. The function of this trap P is to afford a free discharge for air from the radiators when steam is first turned on, and to subsequently prevent waste of steam, 30 trapping off, however, any condensation that may accumulate in the pipe N . When the car is detached from the train this thermostatic trap opens and drains off all condensation from this pipe. The trap P is 35 adapted to open, like the ordinary traps used in steam heating, at a temperature exceeding about 150 degrees F.

To the bottoms of the radiators G are connected pipes R which unite and lead 40 to a low temperature drainage trap S . This trap may be a thermostatic trap of any known construction, a suitable and the preferred construction being that shown in Fig. 3. This trap comprises a shell containing a seat or gasket a , a valve facing b , and a thermostatic vessel or diaphragm c which is seated against the screw cap d of the thermostat shell, this cap having preferably grooves, so as to make intermittent 45 contact with the diaphragm and yet afford the latter adequate support. Whatever construction may be adopted for this drainage trap, the important feature is that it shall operate to open and drain off the water from 50 the radiators whenever the latter fall in temperature to a point sufficiently low to afford danger of ultimate freezing. It is preferable to drain off this water as soon as it cools sufficiently to have no further heating efficiency. It is preferable that the trap shall operate at a temperature of about 60° 55 F., since when the hot water stored in the radiators has fallen to that temperature, it is no longer of any value for heating purposes, while yet it is warm enough to thaw 60

its way out through the drain if perchance the passage be somewhat obstructed by ice.

The steam inlet valve K might be a hand-operated valve, but in the preferred form of the invention it is an automatic valve under thermostatic control. Thermostatically-controlled steam inlet valves are known as applied to passenger cars, wherein a thermostat within the car operates through an electric circuit or some other intervening medium, to control the opening and closing of a steam inlet valve. Such systems would be inapplicable for freight cars because such cars have no electric equipment. Pneumatically-controlled means might possibly be used, utilizing the compressed air of the air brake as the medium, but this is so highly undesirable in practice as to be inhibited. What is desired is a thermo-motive device within the car so sensitive and yet so powerful that it may by direct action operate to open and close the steam inlet valve. Our invention provides such a thermostatic controller, the construction being that best shown in Fig. 1. Within the car is exposed 90 a controlling thermostat T comprising a perforated casing e permitting circulation of air through it, and supporting within it one or more thermo-motive diaphragms (preferably two or more) f consisting of disk-like 95 chambers of thin sheet metal containing a suitably volatile liquid capable of expanding under a low temperature (say 40° F.), so as to expand or bulge the diaphragm vessels, and mechanical means for directly communicating the movement thus generated to the valve stem. As it is preferable to place the vessels in vertical planes, we provide an elbow lever g pivoted at h , for communicating this movement, its horizontal arm pressing downwardly on the valve stem i , which is movable within an outer protecting tube j . The internal construction of the valve may be the same as any ordinary steam admission valve of the globe valve type, consisting for example of a disk or tappet mounted on the bottom end of the stem i , as shown in Fig. 2; or any other suitable valve construction may be used. The important thing is that the valve shall be closed to its seat 105 against the steam pressure by the direct expansion of the thermo-motive vessels f . We proportion the parts so that the valve shall open when the temperature falls to or near 32° F., to admit steam, and shall close when 110 the temperature in the car rises to say 40° F.

When first turning steam into the car with the radiator cold, or whenever it is desired to accelerate the heating effect, the drainage trap P may advantageously be thrown out 115 of action and the steam be permitted to blow directly through this trap. In the case of the ordinary vertical traps having a separate blow-off valve, this is accomplished by opening such blow-off; or in the case of the 120 125 130

use of the particular type of trap illustrated, the thermostatic element of the trap is rendered inoperative by throwing over the control lever h , which operates after the manner set forth in said Patent No. 1,050,210, to unseat the thermostatic valve of the trap and permit the steam to blow through.

The operation of the apparatus will be apparent from the foregoing description.

10 The invention provides a heating system which fully performs all the conditions hereinbefore set forth, being effective to protect the contents of the car from freezing, and with the thermally-controlled inlet valve 15 set forth, being wholly automatic in its operation so long as the car is connected to a locomotive boiler or other source of steam.

It will be understood that our invention is not limited to the precise construction 20 and arrangement herein set forth, these matters being susceptible of a wide range of variation within the terms of the subjoined claims. For example, it is not essential to all features of our invention that the 25 radiator or radiators be located in a radiating

chamber beneath the car floor, having air-circulating flues communicating therewith. nor is our invention limited to the precise construction or type of condensation storage radiator set forth, as other known constructions may be substituted.

What is claimed is:—

A car heating apparatus adapted for protecting freight cars from freezing, comprising a radiator chamber, air-circulating flues 35 communicating therewith, a steam train-pipe, a radiator in said chamber, a branch from said train-pipe, a thermostatic inlet valve controlling said branch pipe, an inlet pipe therefrom entering the radiator, a low 40 temperature trap adapted to drain the radiator, and a high temperature trap connected to the upper part of the radiator.

In witness whereof, I have hereunto signed my name.

EDWARD E. GOLD.

In witness whereof, I have hereunto signed my name.

WILLIAM H. IVERS.
